FLASHLIGHT APPARATUS

Abraham Malkin, New York, N. Y.

Application July 28, 1939, Serial No. 286,995

1 Claim. (Cl. 67—33)

This invention relates to a flashlight apparatus.

The object of the invention is the production of an apparatus by means of which flash powder and the like can be easily ignited.

The second object of the invention is the production of an apparatus with a movable ribbon carrying explosive caps which automatically come in the proper position to be exploded as required, and which in turn ignite a flash powder, instead of igniting the flash powder by sparking a flint, or using a plurality of caps independent of each other and each manually placed in proper position to be exploded.

Various other objects of the invention will be evident from the specification and drawings here-with.

In the drawings, Fig. 1 represents a side elevation of an exemplification of the flashlight apparatus with a partial section as on the line 1, 1 of Fig. 2; Fig. 2 shows a right hand side view with a section on the line 2, 2 of Fig. 1; Fig. 3 indicates an enlarged fragmentary portion of Fig. 1 with some of the movable parts in different positions; and Fig. 4 shows a top view of Fig. 1 with a partial section of Fig. 1 on the line 4, 4.

A longitudinal angle shaped main support comprises the vertical members 20 and 21, at right angles to each other. The member 20 which functions as an anvil is shown with the curved clearance slot 22. The lower edge of the member 20 is indicated at 23, and the member 21 has integral therewith the extension 24, with the bottom flange 25 at right angles thereto. A stop lug 26, extends from the member 21, and a cylindrical handle 27 extends from the flange 25.

A pan 28 comprises the rear vertical wall 30, the front wall 31, the end walls 32, and the bottom wall 33. The wall 30 and the member 20 are fastened to each other by the screws 36, or other means, and a sheet of asbestos 37, or the like, is interposed between the wall 30 and the member 20. An inclined conduit 38 extends through the wall 30, the member 20, and the sheet 37, and leads to the bottom of the pan 28.

To the member 20 is fastened the guide block 40, having the curved lower face 41, and the curved nose 42. A clearance slot 43 extends from the lower face 41 and from the nose 42, and joins with the clearance slot 22.

To the upper portion of the member 21, is secured by welding or other means, the supporting block 45. A shaft 48, extends from the block 45, and has journaled thereon the reel 50, having the

side walls 51, and the central supporting sleeve 52, with the clamping extensions 53, which latter extend from the side walls 51. The outer end of the shaft 48, is threaded for the nut 54. An operating handle 56, extends from one of the side walls 51. A spring 58, is fastened to the upper face of the block 45, by screws as shown, and its free end 59 bears against the face of the adjacent side wall 51.

A main supporting shaft 60, is indicated with the disc flange 61, at its outer end, and its other end 62, of reduced diameter is supported in an opening in the member 21, and clamped in place by the nut 63, as indicated. On the shaft 60, is journaled the driving drum 70, which has integral therewith the ratchet wheel 75. The driving drum 70, has extending from its circumferential surface the driving pins 71, which are rectangular in cross section and equally spaced from one another. To the side face of the drum 70, opposite to the ratchet wheel 75, are fastened the cylindrical camming pins 72. The pins 72 are radially in line with every third driving pin 71. The ratchet wheel 75 has integral therewith the teeth 76.

On the supporting shaft 60, is supported the operating lever having the body portion 80, and the handle 81. An adjusting pin 82, extends from the inner face of the body portion 80, of the operating lever. A pawl 84, is pivoted to the body portion 80, and coacts with the teeth 76 of the ratchet wheel 75. A spring 81, has one end fastened to the body portion 80, and its free end bears on the pawl 84.

A supporting block 90, extends from the member 21, of the main support and has pivoted thereto the pawl 91, which also coacts with the teeth 76, of the ratchet wheel. A spring 93, has one end fastened to a pin 94, extending from the block 90. The free end of the spring 93, bears on the pawl 91. A spring 96, encircles the supporting shaft 60, and has one end fastened to the member 21, and its other end is fastened to the adjacent face of the body portion 80, of the operating lever.

A second shaft 100, has one end 101, reduced in diameter and which is fastened to the extension 24, of the member 21, by means of the nut 102. The other end of the shaft 100, is reduced in diameter as indicated at 104, and on the portion 104, is supported one end of the hammer handle 106, of a hammer having the head 107, with the inclined striking face 108. A release slot 109 is provided in the inner side face of the handle 106. A washer and a nut 110 is provided for

- the portion 104 of the shaft 100. An auxiliary hammer lever 111, inclined to the said hammer handle, has one end supported on the shaft 100. A block 112, connects the hammer handle 106, 5 and the lever 111. A spring 115, which is not as heavy or strong as the spring 96, encircles the shaft 100, and one end 116 thereof is fastened to the hammer handle 106, and its other end is fastened to the shaft 100.
- 10 A ribbon 120, preferably of paper, has connected thereto the circular explosive caps 121, which are larger in diameter than the conduit 38. The said caps are spaced apart so that the distance between the members of each pair of said caps 15 equals the distance between the centers of three of the pins 71. The plane of the longitudinal center line through said caps 121, coincides with a plane extending through the longitudinal center line of the hammer handle 106. Square openings 20 122, are made in the ribbon 120, and which are adapted to engage the driving pins 71. One end of the ribbon 120, is secured in place between the sleeve 52, of the reel 50, and the clamping extensions 53.
- 25 To operate the flashlight apparatus, one end of the ribbon 120, is clamped between the sleeve 52, of the reel 50, and the extensions 53, and the said ribbon is wound around said sleeve by means of the operating handle 56.
- 30 The tension of the spring 96, coacting with the pin 82 of the lever 80, automatically positions the hammer handle 106 with its head 107, in the position indicated in Fig. 1, with the striking face 108 spaced from the member 20, of the main support. The handle 81 of the lever 80, at this instant bears against the lower edge 23 of the member 20.
- 35 The operator then pulls the open end of the ribbon 120, to engage one of the square openings 122, thereof, with one of the driving pins 71, of the driving drum 70, so that one of the explosive caps 121, will be located midway between a pair of the camming pins 72.
- 40 The driving drum 70, is then turned by pulling down the handle 81, and the pawl 84 will engage a tooth of the ratchet wheel 75, whereby the said drum is turned. By this means one of the caps 121, is brought opposite to the conduit 38. Simultaneously one of the camming pins 72, is 45 brought to bear against the hammer handle 106, and swings the same to its open position indicated in full lines in Fig. 3, until the pin 72, is opposite the release slot 109 of said handle 106. When the pin 72, is opposite the release slot 109, the cap 121 is opposite the conduit 38. The hammer handle 106 then swings to its closed position as indicated in dotted lines in Fig. 3, and the explosive cap 121 which is struck explodes and the exploded portion of the cap is shot through the 50 conduit 38, into the flash powder 128, previously placed in the pan 28.
- 55 Attention is called to the fact that when the face 108 of the hammer head 107, strikes one of the caps 121, the blow of the said head is imparted to the said cap at its outer circumferential portion beyond the contour of the conduit 38, because the diameter of the cap is greater than the diameter of said conduit, whereby the central portion of the cap is free to shoot through said 60 conduit.

When the hammer handle 106 is in the dotted position indicated in Fig. 3, the lever 111, is located as shown in dotted lines.

When the handle 106 is located as shown in Fig. 3, in dotted lines the adjusting pin 82 bears 5 against the stop lug 26. When the handle 81 is released, it swings up to the position shown in Fig. 1, by the tension of the heavy spring 96, and the adjusting pin 82 bears against the lever 111, and swings the same to the position as indicated 10 in Fig. 1. At the same time the hammer handle 106 is swung to the position shown in Fig. 1, with its head 107, spaced from the ribbon 120.

The cycle of operations after a cap 121 has been exploded are repeated as required for the 15 ignition of flash powder 128, in the pan 28.

The flashlight apparatus has detachably connected thereto a cover, comprising the front wall 135, having the opening 135a, the side walls 136, and the top wall 138. A pair of lugs 140, extend 20 from the top wall 138, and are positioned to bear against the upper portion of the wall 30, of the pan. Screws 142 detachably clamp the lugs 140, to the said wall 30. When the ribbon 120 is mounted on the reel 50 and connected to the 25 driving drum 70, the cover is detached from the flashlight apparatus by unscrewing the screws 142.

Various modifications may be made in the invention and the present exemplification is to be 30 taken as illustrative and not limitative thereof.

Having described my invention I claim:

A repeating igniter for flashpowder comprising: a frame, a flashpowder receptacle, a ribbon of fulminant caps having perforations intermediate the caps, an anvil having a hole in communication with the receptacle, a spring-actuated hammer member for striking the anvil in alignment with the hole, and mechanism for feeding the ribbon to position the caps on the anvil in 40 alignment with the hole and causing the hammer to strike one of the caps when so positioned to thereby explode the cap and ignite a charge of flashpowder in the receptacle; said mechanism comprising; a drum having guide pins extending 45 radially from its peripheral surface and engaging the holes of the ribbon, camming pins extending from one end face thereof and engageable with the hammer member to retract it as the drum rotates, and a ratchet wheel fixed concentric to the other end face for driving the drum; a spring-biased manually operable lever carrying a spring-pressed pawl which is engageable with the teeth of the ratchet wheel to rotate the drum 55 a predetermined amount upon operation of the lever, a second spring-pressed pawl carried by the frame and engageable with the teeth of the ratchet to prevent reverse rotation of the drum, said hammer member having a slot with which 60 the camming pins cooperate to release it after retraction and thereby enable its actuating spring to swing it toward the anvil, and also an auxiliary lever fixed to the hammer member which is engageable with a pin carried by the manually operable lever to initiate the retracting movement of the hammer member before it is engaged by the camming pins.

ABRAHAM MALKIN.
